UNITED STATES PATENT OFFICE.

CHARLES W. TURNER, OF MASSILLON, OHIO, ASSIGNOR TO MASSILLON-CLEVELAND-AKRON-SIGN COMPANY, OF MASSILLON, OHIO, A CORPORATION.

TWO-WAY SIGN-PRINTING PRESS.

1,401,570.

Specification of Letters Patent. Patented Dec. 27, 1921.

Application filed April 26, 1921. Serial No. 464,576.

To all whom it may concern:

Be it known that I, CHARLES W. TURNER, a citizen of the United States, residing at Massillon, in the county of Stark and State 5 of Ohio, have invented certain new and useful Improvements in Two-Way Sign-Printing Presses, of which the following is a specification.

The present invention relates to improvements in printing machines of that type 10 which are especially designed for the production of "sign," "poster," or "bulletin" work, and which comprise essentially a reciprocating bed and a rotatable impression making cylinder, the object of the invention 15 being to provide a press of this character which embodies novel features of construction whereby a finished printing impression is made for each movement of the reciprocating bed in either direction.

In previous printing machines of this character, such as that disclosed in Patent 20 #1,060,578 to W. M. Bacon and that disclosed in Patent #547,409 to Banta and Black, an arrangement is provided for lifting 25 the printing cylinder when the bed moves in one direction and lowering it to make an impression when the bed moves in the other direction. With these old constructions a complete back and forth movement of the bed is necessary for each printing impression, while with the new construction disclosed by this application a finished printing impression is made for each movement 30 of the reciprocating bed in either direction, thereby practically doubling the possible output of the machine.

Further objects of the invention are to 35 provide a sign printing machine of this character which is dependable in its operation, which enables accurate and clear-cut impressions to be made, which enables a plurality of printing impressions to be made in different colors at the same time when producing certain kinds of work, and which is semi-automatic in its action so that sign and poster work can be produced economically 45 and in a minimum amount of time.

With these and other objects in view, the 50 invention consists in certain combinations, arrangements and associations of the parts, as will be more fully pointed out as the description proceeds, the novel features

thereof being set forth in the appended claims.

For a full understanding of the invention reference is to be had to the following description and accompanying drawings in which:

Figure 1 is a side elevation of a sign 60 printing machine constructed in accordance with the invention.

Fig. 2 is a top plan view thereof.

Fig. 3 is a transverse sectional view on the line 3—3 of Fig. 1, looking in the direction 65 of the arrows.

Fig. 4 is a detail view of the cable connections for driving the reciprocating bed and transmitting motion from the bed to the reciprocating cylinder.

Fig. 5 is a detail view of one end of the printing machine, showing one of the ink fountains and the trip mechanism for automatically raising and lowering the ink distributing roller.

Fig. 6 is an enlarged sectional view on the line 6—6 of Fig. 1, showing the driving mechanism for the reciprocating bed.

Figs. 7 and 8 are detail views of the belt shifting device.

Fig. 9 is a detail view of the printing cylinder, one of the printing surfaces or dies being shown as partially removed therefrom.

Corresponding and like parts are referred to in the following description and indicated 85 in all of the views of the drawings by like reference characters.

Referring in detail to the drawings, which illustrate one possible embodiment of the invention, the numeral 1 designates the supporting frame, 2 a bed which is mounted to reciprocate back and forth upon the supporting frame, and 3 a printing cylinder which is mounted over the reciprocating bed at a point about midway of the back and forth traveling thereof. The supporting frame is of an elongated formation and is provided at the top thereof with the two parallel side rails 4 which are engaged by the supporting wheels or rollers 5 of the bed 2, whereby the bed is properly supported and directed in its back and forth movements. The bed 2 is provided with a plurality of tables which are adjustably mounted thereon so that they can each be accurately positioned in the proper manner for

coöperation with the printing cylinder 3. In the present instance there are three tables, an intermediate impression table 6, and two end tables 7 which are utilized to 5 supply ink or paint to the printing surface of the cylinder 3. Each of the tables is supported at the ends thereof by adjusting screws 8 which can be manipulated in the necessary manner to properly adjust the 10 tables.

The printing cylinder 3 is journaled between the standards 9 which project upwardly from opposite sides of the supporting frame 1 at substantially the middle portion thereof. The upper ends of these standards are shown as provided with bearings 10 which carry the cylinder 3 and which can be moved up and down in the usual manner for the purpose of properly adjusting the 15 cylinder. The back and forth movement of the reciprocating bed under the printing cylinder is such that at the beginning and end of each movement the cylinder engages one of the end tables 7 so that the printing 20 surface thereon is supplied with ink or paint from the said table. One of the end tables 7 is brought under the printing cylinder just before the reciprocating bed reaches the limit of its movement in one direction, while the 25 other table 7 is brought under the printing cylinder just before the reciprocating bed reaches the limit of its movement in the other direction. The printing cylinder is thus supplied with ink or paint so that an impression 30 can be made upon a sheet of metal, glass, wood or other substance which has been placed upon the intermediate impression table 6. The provision of the two end 35 tables 7 which operate to supply paint or ink to the cylinder at each limit of movement of the reciprocating bed thus enables a complete printing impression to be produced for each movement of the reciprocating bed in either direction. As previously 40 explained this very materially increases the output of work and practically doubles the output which is possible with the old type of machine in which a complete back and forth movement of the reciprocating bed is necessary for each impression. 45

During the operation of the printing machine the reciprocating bed is automatically moved back and forth and no attention to the driving mechanism is required on the 50 part of the operator or attendant. Any suitable means may be provided for driving the printing machine, and with the construction which has been illustrated the power is derived from an electric motor 11. From this 55 motor power is transmitted by means of the two belts 12 and 13, of which the latter is crossed, to a counter shaft 14 which is journaled in suitable bearings in the main frame and is provided with the two fixed pulleys 60 15 and the intermediate loose pulley 16. The 65

two belts 12 and 13 are engaged by a belt shifter at 17 so that they can be shifted back and forth upon the fixed and loose pulleys 15 and 16 to drive the counter shaft 14 in either direction. 70

The counter shaft 14 is suitably geared, as indicated at 18, to a transversely disposed drive shaft 19 which is located under the reciprocating bed 2, being journaled upon the supporting frame 1 at substantially the 75 middle portion thereof. A drum 20 is fixed upon the drive shaft 19 and has a cable 21 partially wound thereon. The ends of the cable are extended in opposite directions and have the extremities thereof secured to downwardly extending brackets 22 projecting from opposite ends of the reciprocating beds. A trip lever 23 is arranged at each end of the supporting frame 1 and projects into the path of the reciprocating bed. The lower 80 end of each trip lever is pivoted at 24 to the supporting frame, while the upper end thereof is provided with a triangular block 25 which is adapted to be engaged by the reciprocating bed, and which is so constructed 85 that the engaging face thereof is substantially vertically disposed after the lever has been swung in the manner necessary to actuate the belt shifter and reverse the direction of movement of the bed (see Fig. 95 5). The two trip levers 23 are suitably connected by a rod or cable 26 so that they move in unison, the intermediate portion of the connecting rod or cable engaging a bell crank lever 27 which actuates the belt shifter 100 17 (see Figs. 7 and 8). The shifting of the belts reverses the direction of rotation of the counter shafts 14 and causes the reciprocating bed to be moved in the opposite direction. The two trip levers thus operate to automatically 105 reverse the movement of the reciprocating bed when it reaches the limits of its movement in both directions, and the back and forth movements of the bed are produced automatically. 110

The printing cylinder 3 is rotated as the reciprocating bed moves back and forth, and in order that accurate printing impressions may be made it is obviously necessary for the movement of the printing cylinder to be in perfect synchronism with those of the bed. One end of the printing cylinder is provided with a drum 28 upon which the intermediate portion of a second cable 29 is wound, the ends of the cable extending in opposite directions from the drum and having the extremities thereof secured to brackets 30 which project upwardly from the ends of the reciprocating bed 2. The printing cylinder is thus driven from the reciprocating bed, and the movements of the two members are in perfect synchronism with each other, with the result that the printing surface of the cylinder always maintains the same relation to the impression table 6. 120 125 130

The necessary accurate registry can thus be obtained for doing work in two or more colors.

Any suitable means may be provided for supplying ink or paint to the end tables 7, and the term "ink" as used in the specification and claims is intended to include any analogous substance such as paint, varnish or crayon which might be used in connection with a printing surface or die for making an impression from the die. For the purpose of illustration, conventional ink fountains 33 are shown as applied to the supporting frame at opposite ends thereof and arranged to automatically supply one of the end tables 7 with ink or paint for each movement of the reciprocating bed in either direction. The ink fountains comprise the usual troughs and rollers and need not be described in detail, since they do not constitute any part of the present invention, and any equivalent ink or paint applying means can be substituted. The fountains, however, are preferably only operative during the movement of the bed in one direction. For this purpose the distributing rollers 33^a thereof are shown as carried by bell crank levers 34, said levers having downwardly extending arms which are engaged by a trip rod 35. This rod extends longitudinally of the frame (see Figs. 1 and 4), being supported by suitable guide members and terminating at its extremities in heads or trip members 36 which are arranged to be engaged by the reciprocating bed 2 just as it reaches the limit of its movement in either direction. The distributing roller 33^a of the fountain is thus in a lowered position so as to supply ink or paint to the table 7 as the table passes under the fountain in its movement away from the printing cylinder and toward the end of the frame. After the said end table has been supplied with ink or paint from the fountain the reciprocating bed reaches the limit of its movement and the trip mechanism is operated to lift the distributing roller of the said ink fountain. At the same time the distributing roller of the ink fountain at the opposite end of the machine is lowered so that it will engage the other end table 7 and impart a fresh supply of ink thereto before the bed reaches the limit of its movement in the other direction.

The cylinder 3 may be provided with one or more printing surfaces 37 which may be molded, cut or formed in any suitable manner from any suitable material; and which are preferably wrapped around the cylinder and detachably secured thereto. The printing surfaces can thus be changed as often as is desired or necessary for turning out this work. If desired, a plurality of printing surfaces may be applied to the cylinder so that a corresponding number of printing impressions can be made upon each movement of the reciprocating bed in either direction.

As indicated by Figs. 2 and 9, two printing surfaces 37 are applied to the cylinder, one of them being formed as indicated at 37^a to print a border, while the other is formed as indicated at 37^b to print suitable words. It may be desired to print the border in one color, for instance red, and to print the words in another color, for instance blue, and an arrangement permitting this result to be accomplished is indicated by Fig. 2. The ink fountains at the ends of the printing machine are each shown as formed in two sections, so that each of the end tables 7 will receive red ink or paint at one side thereof as indicated at R, and blue ink or paint on the opposite side thereof, as indicated at B. The arrangement is thus such that the printing surface 37^a for the border will receive red ink or paint from the tables 7, and the printing surface 37^b for the words will receive blue ink or paint.

The intermediate table 6 which constitutes the impression table will receive two plates 40 and 41, and these plates will be held in proper position upon the table by suitable positioning means such as the pins 42. The plate 40 is a plain plate and is placed in position to pass under the printing surface 37^a and have a red border printed thereon. The plate 41 is one which has just gone through the press and has had a border printed thereon upon the previous movement of the reciprocating bed 2, said plate having been shifted to its present position upon the intermediate table 6 from the position now occupied by the plate 40. The plate 43, shown above the printing machine on Fig. 2, is one which has just been removed from the position occupied by the plate 41 and which has received impressions upon the last two movements of the reciprocating bed, the first impression being that of the border, while the second impression was that of the words within the border. Upon the movement of the reciprocating bed to the opposite side of the press, the plate 41 will receive the second impression and will be removed from the press in the condition of plate 43. The plate 40 will then have the border printed thereon and will be in the same condition as plate 41, so that before the reverse movement of the bed, it will be shifted to the opposite side of the table and a plain plate substituted in its place. It will thus be obvious that with the arrangement shown, two complete printing impressions are made upon each movement of the reciprocating bed in either direction, and it will be obvious that by suitable arrangements any number of plates can be printed upon or impressions made, depending upon the size and capacity of the machine and the character of work being done.

The particular construction of the print-

ing machine which I have shown and described is to be considered in an illustrative rather than in a restrictive sense, since it will be obvious that many alterations and changes are possible in the details thereof without departing in any manner from the spirit of the invention.

Having thus described my invention what I claim as new and desire to secure by Letters Patent is:

1. A printing machine of the character described, including a printing cylinder, a reciprocating impression table movable back and forth under the printing cylinder, and means connected to and movable with the table for inking the cylinder after the impression table has passed under the same in either direction, whereby a complete printing impression may be made upon the movement of the table in either direction.

2. A printing machine of the character described, including a printing cylinder, a reciprocating impression table movable back and forth under the printing cylinder, and inking members movable with the table and arranged at opposite ends thereof so that the cylinder will be inked after the impression table has passed under the same in either direction, thereby enabling a complete printing impression to be made upon the movement of the table in either direction.

3. A printing machine of the character described, including a printing cylinder, a reciprocating impression table movable back and forth under the printing cylinder, and inking tables arranged at opposite ends of the impression table for alternate engagement with the printing cylinder to ink the same upon each movement of the table in either direction, thereby enabling a complete printing impression to be made upon each movement of the impression table in either direction.

4. A printing machine of the character described, including a printing cylinder, a reciprocating carriage mounted to move back and forth under the cylinder, spaced inking tables upon the carriage, an impression table arranged intermediate the inking tables, and means for independently adjusting the tables upon the carriage, the provision of the two inking tables enabling a complete printing impression to be made upon each movement of the carriage in either direction.

5. A printing machine of the character described, including a printing cylinder, a reciprocating impression table movable back and forth under the printing cylinder, inking tables arranged upon opposite sides of the impression table and movable therewith, and means for automatically supplying ink to one of the tables upon each movement of the tables in either direction, the provision of the two inking tables enabling a complete

printing impression to be made upon each movement of the impression table.

6. A printing machine of the character described, including a printing cylinder, a reciprocating impression table movable back and forth under the printing cylinder, inking tables movable with the impression table and arranged upon opposite side thereof for alternate engagement with the printing cylinder, and fountains arranged upon opposite sides of the printing cylinder for supplying ink to the corresponding inking tables as the tables approach the limit of their movements in different directions, the provision of the two inking tables enabling a complete printing impression to be made upon each movement of the table in either direction.

7. A printing machine of the character described, including a printing cylinder, a reciprocating impression table movable back and forth under the printing cylinder, inking tables movable with the impression table and arranged upon opposite sides thereof for alternate engagement with the printing cylinder, fountains arranged upon opposite sides of the printing cylinder for supplying ink to the corresponding inking tables, and means for rendering the fountains inoperative upon the movement of the tables in one direction and operative upon the movement of the tables in the other direction, the provision of the two inking tables enabling a complete printing impression to be made upon each movement of the impression table in either direction.

8. A printing machine of the character described, including a printing cylinder, a reciprocating carriage movable back and forth under the printing cylinder, three tables mounted upon the carriage, the intermediate table constituting an impression table while the end tables constitute inking tables, means for independently adjusting the tables upon the carriage, and means for supplying ink to the corresponding inking tables as the latter approach the limits of their movements away from the printing cylinder, the provision of the two inking tables enabling a complete printing impression to be made upon each movement of the impression table in either direction.

9. A printing machine of the character described, including a printing cylinder, provided with a plurality of independent printing surfaces, a reciprocating impression table movable back and forth under the printing cylinder, and an inking table movable with the impression table and adapted to carry different colors of ink for application to the different printing surfaces whereby independent impressions may be made from the different printing surfaces upon each operative movement of the impression table under the printing cylinder.

10. A printing machine of the character described including a printing cylinder provided with a plurality of independent printing surfaces, a reciprocating impression table movable back and forth under the printing cylinder, inking tables movable with the impression table and arranged upon opposite ends thereof for alternate engagement with the printing cylinder, and means 5 upon opposite sides of the printing cylinder for supplying different colors of ink to the respective printing tables as the latter approach the limits of their movements away from the printing cylinder, the different colors of inks being applied to the different surfaces of the cylinder and the provision of the two inking tables enabling a com- 10

plete printing impression to be made from each of the printing surfaces upon each movement of the impression table in either 20 direction.

11. A printing machine of the character described, including a printing cylinder, a reciprocating impression table movable back and forth under the printing cylinder, and 25 a pair of independent inking means acting alternately to ink the printing cylinder as the impression table is moved in opposite directions, thereby enabling a complete printing impression to be made upon the move- 30 ment of the table in either direction.

In testimony whereof I affix my signature.

CHARLES W. TURNER.
